UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

ELECTRIC IRON.

Application filed May 9, 1923. Serial No. 637,754.

To all whom it may concern:

Be it known that I, ORA A. COLBY, a citizen of the United States, and a resident of Irwin, in the county of Westmoreland and 5 State of Pennsylvania, have invented a new and useful Improvement in Electric Irons, of which the following is a specification.

My invention relates to electric heating devices and particularly to electric irons.

10 One object of my invention is to provide an electric iron of relatively simple and inexpensive construction and that shall employ relatively few parts and shall be easily and quickly assembled and disassembled.

15 Another object of my invention is to provide a relatively simple and inexpensive heating element for an electric iron.

Another object of my invention is to provide a relatively simple terminal construction 20 for the heating element of an electric iron.

In practicing my invention, I provide a sole plate, of substantially triangular contour, having a longitudinally extending 25 chamber therein, said chamber being wider at the rear end of the iron than at the front end thereof. Two tubes of electric insulating material are located in the chamber adjacent to the side walls thereof and a continuous electric resistor member is located 30 in said tubes.

A filling of granular electric-insulating and heat-conducting material is provided 35 in the chamber and in the tubes. An electric insulating member that is interlocked with the rear portion of the sole plate is provided to close the chamber and to hold the tubes in their proper operative positions 40 therein and this member carries suitable contact terminal members electrically connected to the ends of the resistor.

A cover member is provided for the iron and it is effective also to securely hold the interlocked member in its proper operative 45 position against the top of the iron.

In the single sheet of drawings,

Figure 1 is a view, partly in longitudinal vertical section and partly in side elevation, 50 of an electric iron comprising the device embodying my invention.

Fig. 2 is a top plan view thereof, with the cover and the handle member removed and a portion of the top cut away, and

55 Fig. 3 is a view, in vertical lateral section thereof, taken on the line III—III of Fig. 1.

An electric iron designated generally by the numeral 11 comprises a sole plate 12, the bottom or working surface of which is suitably smoothed and polished, as is usual in the art.

The member 12 may be of substantially triangular contour and is provided with a longitudinally extending chamber 13 of relatively low height, which chamber is relatively narrow at the front end of the sole plate, and is relatively wide at the rear end thereof. Integral side portions 15 of the sole-plate are provided at each side adjacent to the rear edge thereof and are located above the bottom portion of the sole plate 12. The inner opposing faces thereof are angularly disposed relatively to each other to provide a relatively wide opening 16 of dove-tail shape, therebetween for a purpose to be hereinafter set forth in detail.

The top portion 14 of the sole plate does not extend outwardly to a plane immediately above the rear edge of the sole plate 12 but terminates immediately inside of the hereinbefore described dove-tail opening 16.

A cover member 17, of substantially the same contour as the sole plate 12, is located thereabove and is held in its proper operative position by a single machine screw 18 extending therethrough and into an integral upstanding lug 19 on the top portion 14. A handle strap 21 is secured against the upper surface of the cover member 17 by rivets 22 and has secured thereto at the upper ends thereof a suitable handle 23.

A heating element for the iron comprises two tubes 24, of electric-insulating material, that are located in the chamber closely adjacent to the walls constituting the sides thereof. The front end of each of the tubes 24 is provided with a beveled portion 25 which may be obtained by cutting off a small portion of each of the tubes 24 angularly relatively to the tubes themselves. The amount of material cut off is such as will permit of locating the front ends of the two tubes in close operative engagement relatively to each other and relatively also to the walls of the chamber 13. This construction permits of locating the two tubes in their proper operative positions in the front end of the chamber 13 and prevents any turning movement of the two tubes relatively to each other.

A resistor member 26 comprises a helical coil of a suitable resistor material, that is

substantially co-extensive with the length of the two tubes 24. The resistor member 26 is placed in its proper operative position within the two tubes 24 while these tubes are 5 located in substantially axial alinement relatively to each other, after which the two tubes are disposed angularly and adjacent to each other and placed in the chamber 13 in substantially the positions shown in Fig. 10 2 of the drawing.

The chamber 13 and the tubes 24 are then 15 filled with a mass 27 of granular electric-insulating and heat-conducting material, such as alundum. During this operation, 15 the iron may be held tipped up on its front end in a suitable holder.

The ends of the resistor member 26 are 20 suitably secured to terminal straps 28, the lower ends of which are suitably insulated 20 from the sole plate 12 by sheets 29 of an electric insulating material, such as mica. Terminal pins 31 are suitably secured to the upper ends of the terminal straps 28 by 25 any suitable means, such as a machine screw 32.

A member 33, of suitable electric-insulating and heat-insulating material and of L-shape in lateral section, is provided to close the opening of the chamber 13. The member 30 33 is located within the dove-tail opening 16 and is interlocked therewith by having its sides beveled to conform to the bevel of the integral positions 15. This member 35 is placed in its proper operative position by moving it in a direction at right angles to the working surface of the sole plate 12. If desired, a relatively thin sheet 34, of asbestos, may be placed between the member 33 and the rear ends of the tubes 24, 40 whereby a more resilient closure of the chamber 13 is effected.

The heating element of the iron may be 45 energized by the usual twin supply circuit conductor 35, the ends of which are suitably secured to contact sockets (not shown) located in a contact plug 36, the contact sockets being adapted to operatively engage the contact pins 31. A helical spring 37 may be provided in the plug 36 to prevent undue kinking or bending of the supply circuit 35.

A guard for the terminal pins 31 and for 55 the plug 36 may comprise a suitably punched and shaped metal member 38 having integral depending portions 39 and an integral forwardly extending portion 41 for permitting of securing the same against the top of the cover 17 by one of the rivets 22. A suitable opening 42 is provided in the 60 rear of the top portion of the cover member 17 through which the terminal pins 31 may extend.

The dimensions of the member 33 are such 65 as to cause it to fit closely between the cover member and the upper surface of the rear

edge of the bottom portion of the sole plate 12 when the cover member is held in its proper operative position by the bolt 18. This fixes the position of the terminal pins 31 which as has hereinbefore been described, 70 are suitably mounted in the member 33.

A sheet metal member 43, of substantially L-shape, may have one portion thereof secured to the inside of the cover member 17, and have its outwardly extending portion 75 return bent, substantially as shown in Fig. 1 of the drawing. The member 43 co-operates with the plug 36 or with the outer edge of the guard 38 to support the iron in a 80 backwardly-tilted position whenever desired.

The chamber 13 may be suitably cored out and does not require any machining operations. The lateral dimensions of the chamber 13 may be made any suitable value 85 in order to co-operate with the granular heat-conducting material located therein to provide a relatively uniform temperature over the entire working surface of the bottom of the sole plate 12. The member 33, 90 being interlocked with the sole plate 12, holds the tubes 24 in their proper operative spaced positions in the iron and if it is necessary to replace the heating element, this member may be easily and quickly removed from its operative engagement with the sole plate after the cover member has 95 been removed. After this, the tubes and the resistor member located therein may also be easily and quickly removed and new ones substituted therefor.

Various modifications and changes may be made without departing from the spirit and scope of the invention, and I desire, therefore, that only such limitations shall be placed thereon as are imposed by the prior art or are set forth in the appended claims.

I claim as my invention:

1. An electric iron comprising a longitudinally chambered sole plate, a plurality of tubular electric insulating members in said chamber, an electric resistor member in said tubular members and means interlocked with said sole plate for holding said tubular members in proper operative positions in said chamber.

2. An electric iron comprising a longitudinally chambered sole plate, a plurality of tubular electric-insulating members in said chamber, a continuous resistor member in said tubular members, a filling of granular electric-insulating, and heat-conducting material in said chamber and in said tubular members, and means interlocked with said sole plate for holding said tubular members in proper operative positions in said chamber.

3. An electric iron comprising a longitudinally chambered sole plate, a plurality

- of tubes of electric-insulating material in said chamber and operatively engaging the side walls thereof, a continuous electric resistor in said tubes, a filling of granular, electric-insulating and heat-conducting material in said chamber and said tubes, and an electric insulating member, interlocked with said sole plate, for closing said chamber and for holding said tubes in proper operative positions in said chamber.
4. An electric iron comprising a longitudinally chambered sole plate, a plurality of tubes of electric-insulating material in said chamber and operatively engaging the side walls thereof, a continuous electric resistor in said tubes, a filling of granular, electric-insulating and heat-conducting material in said chamber and said tubes, an electric-insulating member interlocked with said sole plate, for closing said chamber and for holding said tubes in proper operative positions in said chamber and a cover member on said sole plate for covering the same and for holding said electric-insulating member against an upper surface of said sole plate.
5. An electric iron comprising a longitudinally chambered sole plate, a plurality of tubes of electric-insulating material in said chamber and operatively engaging the side walls thereof, a continuous electric resistor in said tubes, a filling of granular, electric-insulating and heat-conducting material in said chamber and said tubes, an electric-insulating member interlocked with said sole plate, for closing said chamber and for holding said tubes in proper operative positions in said chamber and a cover member on said sole plate for covering the same and for holding said electric-insulating member against an upper surface of said sole plate.

In testimony whereof, I have hereunto subscribed my name this 7th day of May 1923.

ORA A. COLBY.
